UNITED STATES PATENT OFFICE

2,273,705

RAILROAD SAFETY DEVICE

Diego Guerrero, Brooklyn, N. Y.

Original application December 1, 1939, Serial No. 307,127. Divided and this application November 5, 1940, Serial No. 364,350

6 Claims. (Cl. 104—248)

This application is a division of my application, Serial No. 307,127, filed December 1, 1939, for Railroad safety devices.

This invention relates to railroad safety devices, and is particularly directed to means for preventing derailment of the trucks or cars of either a toy railroad car or regular railroad.

An object of this invention is to provide a safety device for toy railroads, including a frame having parallel longitudinal members slidably mounted on the wheel axles of the truck, and fins at the ends of each of said members, disposed above the head of the rail and beneath the inner portion of the head of the rail and normally having a clearance with respect to the rail, except when called into play to prevent derailment, spring units being further provided between the ends of said longitudinal members to resiliently press said members apart, whereby the safety fins may be snapped into position to facilitate application of the toy truck to the rails or removal of the truck therefrom.

The purpose of the upper fin is to make it a more perfect miniature of a real regular rail of the type I am endeavoring to patent for regular railroads in my above-identified patent application.

A further object of this invention is to provide a strong, rugged and durable rail safety device of the character described, which shall be relatively inexpensive to manufacture, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a top plan view of toy rail tracks and a truck mounted thereon and provided with safety derailment device, embodying the invention.

Fig. 2 is a side elevational view of the structure shown in Fig. 1.

Fig. 3 is a cross-sectional view taken on line 3—3 of Fig. 1.

Fig. 4 is an enlarged cross-sectional view taken on line 4—4 of Fig. 2.

Fig. 5 is a cross-sectional view taken on line 5—5 of Fig. 4.

Fig. 6 is a cross-sectional view taken on line 6—6 of Fig. 4.

Fig. 7 is a top plan view of the safety frame.

Fig. 8 is an enlarged detailed view of a portion of Fig. 6.

Referring now in detail to the drawings, Figs. 1 to 6 are directed to toy railroad construction, embodying the invention, designated by numeral 10. Said railroad construction comprises rail ties 11, on which are mounted rails 12 attached to the ties, in any suitable manner, and a third rail 14 mounted on the ties 11 and disposed between the rails 12.

On the rails 12 is a truck 15 supporting a car 16. The truck 15 may be of usual construction and comprises a pair of side frames 17 carrying parallel axles 18, on which are carried wheels 19, rolling on the rails 12. The side frames 17 are inter-connected by the usual spring assembly 20, 21, on which the car 16 is mounted.

Means is provided to prevent the derailment of the truck. To this end, there is slidably mounted on the axles, and disposed between the wheels 19, a safety frame 25. The same comprises a pair of similar, symmetrically disposed, parallel, longitudinal side members 26 disposed beneath the spring assembly 21 and formed with semi-cylindrical notches 27 to receive the axles.

Bolted to the members 26, are members 28 formed with semi-cylindrical notches to receive said axles. The side members 26 are thus slidably mounted on the axles and may be moved toward one another, as will appear hereinafter.

Each side member 26 is formed with threaded openings 30 at its outer ends. Riveted to the outer end of each member 26, as by rivets 31, is a member 32 having a wall 33 contacting the outer surface of said side member 26. Each member 26 has an inwardly extending arm 34 disposed at right angles to said wall 33. Extending downwardly from wall 33 is a wall 35 formed with an outwardly extending portion or fin 36, disposed above the head 12^a of the rail 12, and a downwardly extending portion or fin 37 disposed beneath the inner side of the rail head 12^a. Each wall 33 is formed with a threaded opening 39 registering with one of the threaded openings 30.

To limit movement of members 26 away from each other, there is provided at each end of the safety frame 25, a strap member 42 having parallel arms 44 overlying walls 33, and formed with openings 43, and a portion inter-connecting said arms.

Screwed within the openings 30 and 39 are aligned, symmetrical, inwardly extending pins 47,

loosely passing through the opening 43 and formed with reduced inner end portions 48, for the purpose hereinafter appearing.

Mounted on each pair of aligned pin portions 48, is a sleeve 50 slidably receiving said pin portions, and disposed parallel to strap 42. On each of the ends of the sleeves 50 is a sleeve 51. Interposed between the sleeves 51, and disposed on sleeve 50, is a coil compression spring 52 serving to push the sleeves 51 apart, and thus serving to press the members 26 away from each other. On sleeve 51 is an outer loose sleeve 54, surrounding and covering the spring 52.

Thus, the springs 52 serve to press the members 26 apart, whereas, the strap members 42 limit movement of said side members 26 away from each other. By pressing the side members 26 toward each other, the fins of the flanges 38 are moved a sufficient distance inwardly, so that the truck may be lifted off the rail. When the truck is mounted on the rail, side members 26 are first pressed toward each other, and the truck placed on the rail. The side members are then released, so that the springs 52 snap the safety devices 32 into position for preventing derailment of the truck.

It will be noted that under ordinary conditions, the flanges or fins 36 and 37 of the flanges 38 do not contact the rail head or the rail, so that there is no friction or wearing of parts.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings, is to be interpreted as illustrative and not in a limiting sense.

Having thus described my invention, what I claim as new, and desire to secure by United States Letters Patent is:

1. A railroad truck having an axle carrying wheels engageable on a pair of spaced tracks, a pair of longitudinal members slidably mounted on said axle to move laterally of said truck, downwardly extending fins formed on the ends of said members and engageable with the inside faces of the heads of said tracks to prevent derailment of the truck, means for limiting the outward movement of said members to positions in which said fins will be in close proximity to the inside faces of said heads, a sleeve of a length shorter than the space between the adjacent faces of said members, means supporting said sleeve between the ends of said members, a pair of spaced sleeves on said first sleeve, and resilient means on said first sleeve and operating between the inner ends of said second sleeve for spreading said second sleeves to cause their outer ends to engage the inner faces of said members and spread said members to cause said fins to be disposed in close proximity to the inside faces of the heads of said tracks, whereby said members may be squeezed together against the action of said resilient means to disengage said fins from beneath said track heads permitting said truck to be removed from said tracks.

2. A railroad truck having an axle carrying wheels engageable on a pair of spaced tracks, a pair of longitudinal members slidably mounted on said axle to move laterally of said truck, downwardly extending fins formed on the ends

of said members and engageable with the inside faces of the heads of said tracks to prevent derailment of the truck, means for limiting the outward movement of said members to positions in which said fins will be in close proximity to the inside faces of said heads, a sleeve of a length shorter than the space between the adjacent faces of said members, means supporting said sleeve between the ends of said members, a pair of spaced sleeves on said first sleeve, and resilient means on said first sleeve and operating between the inner ends of said second sleeves for spreading said second sleeves to cause their outer ends to engage the inner faces of said members and spread said members to cause said fins to be disposed in close proximity to the inside faces of the heads of said tracks, whereby said members may be squeezed together against the action of said resilient means to disengage said fins from beneath said track heads permitting said truck to be removed from said tracks, said first-mentioned means comprising parallel laterally extending members disposed between the ends of said longitudinal members, and right angular flange portions extended along the outside faces of said longitudinal members.

3. A railroad truck having an axle carrying wheels engageable on a pair of spaced tracks, a pair of longitudinal members slidably mounted on said axle to move laterally of said truck and formed with aligned openings, downwardly extending fins formed on the ends of said members and engageable with the inside faces of heads of said tracks to prevent derailment of the truck, means for limiting the outward movement of said members to positions in which said fins will be in close proximity to the inside faces of said heads, a sleeve of a length shorter than the space between the adjacent faces of said members supported between the ends of said members, a pair of spaced sleeves on said first sleeve, and resilient means on said first sleeve and operating between the inner ends of said second sleeves for spreading said second sleeves to cause their outer ends to engage the inner faces of said members and spread said members to cause said fins to be disposed in close proximity to the inside faces of said heads, a sleeve of a length shorter than the space between the adjacent faces of said members, means supporting said sleeve between the ends of said members, a pair of spaced sleeves on said first sleeve, and resilient means on said first sleeve and operating between the inner ends of said second sleeves for spreading said second sleeves to cause their outer ends to engage the inner faces of said members and spread said members to cause said fins to be disposed in close proximity to the inside faces of said heads, whereby said members may be squeezed together against the action of said resilient means to disengage said fins from beneath said track heads permitting said truck to be removed from said tracks, said first-mentioned means comprising parallel laterally extending members disposed between the ends of said longitudinal members, and right angular flange portions extended along the outside faces of said longitudinal members and having openings in aligned positions with the openings in said longitudinal members, said support for said first-mentioned sleeve, comprising pins freely extended through the openings in said flange portions and threadedly engaged through the openings in said longitudinal members and having ends extended freely into the open ends of said first-mentioned sleeve.

4. A railroad truck having an axle carrying wheels engageable on a pair of spaced tracks, a pair of longitudinal members slidably mounted on said axle to move laterally of said truck and formed with aligned openings, downwardly extending fins formed on the ends of said members and engageable with the inside faces of the heads of said tracks to prevent derailment of the truck, means for limiting the outward movement of said members to positions in which said

fins will be in close proximity to the inside faces of said heads, a sleeve of a length shorter than the space between the adjacent faces of said members supported between the ends of said members, a pair of spaced sleeves on said first sleeve, and resilient means on said first sleeve and operating between the inner ends of said second sleeves for spreading said second sleeves to cause their outer ends to engage the inner faces of said members and spread said members to cause said fins to be disposed in close proximity to the inside faces of the heads of said tracks, whereby said members may be squeezed together against the action of said resilient means to disengage said fins from beneath said track heads permitting said truck to be removed from said tracks, said first-mentioned means comprising parallel laterally extending members disposed between the ends of said longitudinal members, and right angular flange portions extended along the outside faces of said longitudinal members and having openings in aligned positions with the openings in said longitudinal members, said support for said first-mentioned sleeve comprising pins freely extended through the openings in said flange portions and threadedly engaged through the openings in said longitudinal members and having ends extended freely into the open ends of said first-mentioned sleeve, said pins having their heads spaced from the outer faces of said flange members permitting said longitudinal members to be moved inwards until said heads strike the outside faces of said flange members.

5. A railroad truck having an axle carrying wheels engageable on a pair of spaced tracks, a pair of longitudinal members slidably mounted on said axle to move laterally of said truck and formed with aligned openings, downwardly extending fins formed on the ends of said members and engageable with the inside faces of the heads of said tracks to prevent derailment of the truck, means for limiting the outward movement of said members to positions in which said fins will be in close proximity to the inside faces of said heads, a sleeve of a length shorter than the space between the adjacent faces of said members, means supporting said sleeve between the ends of said members, a pair of spaced sleeves on said

first sleeve, and resilient means on said first sleeve and operating between the inner ends of said second sleeves for spreading said second sleeves to cause their outer ends to engage the inner faces of said members and spread said members to cause said fins to be disposed in close proximity to the inside faces of the heads of said tracks, whereby said members may be squeezed together against the action of said resilient means to disengage said fins from beneath said track heads permitting said truck to be removed from said tracks, said resilient means, comprising a spring coaxially mounted on said first-mentioned sleeve and bearing against the inner ends of each pair of spaced sleeves.

6. A railroad truck having an axle carrying wheels engageable on a pair of spaced tracks, a pair of longitudinal members slidably mounted on said axle to move laterally of said truck, downwardly extending fins formed on the ends of said members and engageable with the inside faces of the heads of said tracks to prevent derailment of the truck, means for limiting the outward movement of said members to positions in which said fins will be in close proximity to the inside faces of said heads, a sleeve of a length shorter than the space between the adjacent faces of said members, means supporting said sleeve between the ends of said members, a pair of spaced sleeves on said sleeve, and resilient means on said first sleeve and operating between the inner ends of said second sleeves for spreading said second sleeves to cause their outer ends to engage the inner faces of said members and spread said members to cause said fins to be disposed in close proximity to the inside faces of the heads of said tracks, whereby said members may be squeezed together against the action of said resilient means to disengage said fins from beneath said track heads permitting said truck to be removed from said tracks, said resilient means, comprising a spring coaxially mounted on said first-mentioned sleeve and bearing against the inner ends of each pair of spaced sleeves, and a cover sleeve of a length equal to the length of said first-mentioned sleeve and engaged over the inner ends of each pair of spaced sleeves and said springs.

DIEGO GUERRERO.
